(57) **CLAIM**

The ornamental design for an egg carton, as shown and described.

DESCRIPTION

FIG. 1 is a perspective view of an embodiment of my egg carton in an open configuration;

FIG. 2 is a front view thereof;

FIG. 3 is a rear view thereof;

FIG. 4 is a left side view thereof;

FIG. 5 is a right side view thereof;

FIG. 6 is a top view thereof; and

FIG. 7 is a bottom view thereof;

FIG. 8 is a perspective view of another embodiment of my egg carton in an open configuration;

FIG. 9 is a front view thereof;

FIG. 10 is a rear view thereof;

FIG. 11 is a left side view thereof;

FIG. 12 is a right side view thereof;

FIG. 13 is a top view thereof; and,

FIG. 14 is a bottom view thereof.

The broken lines shown in the drawings illustrate portions of the egg carton that form no part of the claimed design.

The egg carton is shown with a symbolic break in both its length and width, represented by multiple break lines. The
